UNITED STATES PATENT OFFICE.

WILLIAM H. TEACHOUT, OF HERKIMER, NEW YORK, ASSIGNOR OF ONE-HALF TO OWEN COONS, OF SAME PLACE.

DESIGN FOR A KITCHEN-CABINET.

SPECIFICATION forming part of Design No. 31,650, dated October 10, 1899.

Application filed June 21, 1899. Serial No. 721,385. Term of patent 7 years.

To all whom it may concern:

Be it known that I, WILLIAM H. TEACHOUT, a citizen of the United States, residing at Herkimer, in the county of Herkimer and State 5 of New York, have invented a new and original Design for Kitchen-Cabinets, of which the following is a specification, reference being had to the accompanying drawing, forming part thereof, and in which similar letters 10 refer to similar parts.

The drawing represents a perspective view of a kitchen-cabinet of my design.

As shown in the drawing, A represents the upper portion of the cabinet, having a paneled front, the upper panels *a'* being the fronts of two doors of a cupboard, the panels *b'* being the fronts of a horizontal row of drawers located below the said doors, the panels *c'* being the fronts of two drawers situated below the said horizontal row of drawers, one at each end thereof. The panels *d'* represent four brackets, two of which are arranged in the corners between the upper and lower drawers, and the other two in the corners between the lower drawers and the side pieces, hereinafter mentioned.

E represents the base or lower portion of the cabinet and which is substantially rectangular in shape. Between the said upper 30 and lower portions of the cabinet are two side pieces, having their front edges curved.

By reference to the drawing it will be seen that the upper portion is about half as deep as the lower portion. The lower portion of 35 the cabinet is provided with a paneled front, the upper panel *e'* representing the front of a

sliding bread-board and the central panels *j* the fronts of three drawers arranged one above the other. The panels *f'* represent the fronts of two flour-bins, said flour-bins being 40 located one on each side of the said central drawers.

The essential features of my design consist of a kitchen-cabinet having one upper and one lower portion, the upper portion being of 45 about half the depth of the lower portion and provided at its front with two upper panels, representing the fronts of two doors, and a horizontal row of panels representing the fronts of drawers located below the said doors, 50 the lower portion of the cabinet being substantially rectangular in shape and provided at its front with one upper panel, representing the front of a sliding bread-board, three central panels representing the fronts of three 55 drawers arranged one above the other, and two side panels representing the fronts of two flour-bins located one on each side of the said drawer, two side pieces located between the upper and lower portions of the cabinet, said 60 side pieces having their front edges curved, substantially as hereinbefore set forth.

Having thus described and illustrated my invention, what I claim as new, and desire to secure by Letters Patent, is—

The design for a kitchen-cabinet substantially as shown and described.

WILLIAM H. TEACHOUT.
